(57) **CLAIM**

The ornamental design for bag, as shown and described.

DESCRIPTION

FIG. 1 is a front perspective view of a bag showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an alternative embodiment of the bag shown in FIG. 1;

FIG. 9 is a front view thereof;

FIG. 10 is a back view thereof;

FIG. 11 is a left side view thereof;

FIG. 12 is a right side view thereof;

FIG. 13 is a top view thereof;

FIG. 14 is a bottom view thereof;

FIG. 15 is another alternative embodiment of the bag shown in FIG. 1;

FIG. 16 is a front view thereof;

FIG. 17 is a back view thereof;

FIG. 18 is a left side view thereof;

FIG. 19 is a right side view thereof;

FIG. 20 is a top view thereof; and,

FIG. 21 is a bottom view thereof.

In the drawings, the broken lines shown on the bag represent stitching and form a part of the claimed design. The additional broken lines on the handle and chain portion of the bag form no part of the claimed design.
